CLAIM

The ornamental design for a wall mountable bracket, as shown and described.

DESCRIPTION

FIG. 1 is a left, top, front perspective view of a wall mountable bracket embodying my new design;

FIG. 2 is a left side elevational view thereof, the right side elevational view being a mirror image of the left side shown;

FIG. 3 is a front elevational view thereof;

FIG. 4 is a top plan view thereof; and,

FIG. 5 is a bottom plan view thereof.

The broken line representation of holes in FIGS. 1 and 3 is for purpose of illustration only, and forms no part of the claimed design.
